UNITED STATES PATENT OFFICE

ROBERT F. HALL, OF SCHENECTADY, NEW YORK

TRUCK FOR RAILWAY ROLLING STOCK

Application filed July 10, 1929. Serial No. 377,164.

This invention relates generally to trucks for railway rolling stock of the class or type wherein lateral resistance devices are provided, as set forth in Letters Patent of the United States No. 1,512,463 and No. 5 1,533,245 issued to me under the dates of October 21, 1924, and April 14, 1925 respectively.

The present invention particularly relates 10 to further improvements in swing hanger links by which the bolster is suspended from the truck frame, and its object is to provide a novel construction wherein the lateral resistance shall slowly increase with respect to 15 the displacement of the bolster from a central position and will consume a minimum of space.

The improvement claimed is hereinafter 20 fully set forth.

In the accompanying drawings: Figure 1, 25 is a front view partly in section of a truck equipped with four point hangers embodying the invention; Fig. 2, a section on the line II-II of Fig. 1; Fig. 3, a view similar to Fig. 1, except that the bolster is shown deflected laterally; and, Fig. 4, a coordinate diagram illustrating the lateral resistance characteristics of the structure of Figs. 1 30 to 3.

In the practice of the invention, referring 35 descriptively to the specific embodiment thereof which is herein exemplified, as applied to a two wheeled locomotive truck of the swing or lateral motion type, a frame 1, is suspended through the intermediation of 40 springs 2, on the journal boxes 3, of an axle 4, on which the wheels 5 are secured. A swing frame or bolster support 6, extends from one to the other of the side members of the truck frame 1, to which it is fixed at its 45 ends, as by being made integral therewith or otherwise. The weight of the superstructure of the vehicle is primarily applied to the truck frame through the swing bolster 7, provided with means for pivotally engaging the center pin 8. The bolster 7, is suspended with the capacity for lateral movement relatively to the frame 6, by the swing hanger links 17, hereinafter de- 50 scribed.

In Fig. 1, the truck is shown with the bolster 7 in normal or central position with respect to the frame 6, as when the vehicle is on tangent track. Each of the links 17, are provided with seats for four pins, the upper two of which rest on the pins 13, and 14, attached to the frame 6, and the lower two support the pins 15 and 16, attached to the bolster. In order to obtain the desired character of lateral resistance, the pins are positioned as follows: When the bolster is central, as in Fig. 1, a vertical line is projected through the axis of the outermost lower or bolster pins 15, and the upper, or frame pins 13 and 14, are positioned horizontally, on opposite sides of said vertical through pin 15, and the lower pin 16, is suitably positioned, horizontally, between the pin 15, and the central vertical plane of the truck. It is obvious that the placement of the pins may be varied in accordance with the character of the resistance that is desired.

By reference to Fig. 3, it will be seen that when the bolster 7 commences to deflect to the left, the effective bearings in the right hand swing hanger link 17 are on the pins 13 and 16, and in the left hand swing hanger link, on the pins 14 and 15. For a given deflection of the bolster 7, the inclination to the vertical of the lines joining the axes, respectively, of these effective pins is found to be greater than in the three point type of suspension, and therefore, the initial lateral resistance, in proportion to the load, will also be greater.

Also, it has been found, as will be noted from Fig. 3 that the tipping of the bolster or the deflection increases, due to the difference in the slopes of the supporting hangers, tends to transfer a greater proportion of the weight imposed through the pivotal connection of the center pin 8, to the left hand bolster pin 15, and the effective inclination of the left hand link 17, as denoted by the line passing through the axes of the effective pins 14 and 15, being less than the effective inclination of the right hand link 17, as denoted by the line passing through the axes of the effective pins 13 and 16, it follows that the lateral resistance derived there-

from will also proportionately decrease as the said tipping of the bolster 7, becomes more pronounced. This action results in a lateral resistance characteristic if the dimensions of the parts be suitably chosen, that may be exemplified by the curve F of Fig. 4.

Fig. 4, is a coordinate diagram wherein the abscissæ are proportionate to the lateral deflections of the pivotal connection of the center pin and bolster with respect to the truck frame, 6, and the ordinates are proportionate to the lateral resistance, or horizontal returning force exerted at said pivotal connection.

15 Were the application of the load to the bolster applied in such a manner that the vertical axis through the center of gravity thereof remained at a constant distance, horizontally from the axes of the effective 20 bolster supporting pins, as, with reference to Fig. 3, the right hand pin 16, and the left hand pin 15, a result commonly obtained in practice when the bolster and center pin are continuous or integral, the relation of lateral resistance would be expressed 25 by the curve D of Fig. 4, wherein the said lateral resistance is shown to increase very rapidly with respect to the deflection.

The relative height of the pivotal connection 30 between the center pin 8 and the bolster 7 is an important factor in the design of the coacting parts to produce the desired character of lateral resistance illustrated by the curve F of Fig. 4, if this said height be 35 made materially less than that contemplated in the drawings, resistance characteristics exemplified by the curve E of Fig. 4, would result.

The invention claimed and desired to be 40 secured by Letters Patent, is:

1. A swing hanger link for lateral motion railway trucks, having two upper and two lower bearings, the upper bearings being disposed on opposite sides of the middle line of 45 the link at unequal distances from the lower bearings.

2. A swing hanger link for lateral motion railway trucks having two upper and two lower bearings, the two upper bearings being disposed, horizontally, on opposite sides of a vertical through the outermost lower bearing.

3. In a truck for railway vehicles, the combination of a frame; a weight-supporting 55 bolster adapted to traverse laterally relative thereto; pivotal means interposed between the bolster and the weight; and swing links supporting said bolster, and provided each with upper bearings and lower bearings so disposed that the distances between them are 60 unequal.

4. In a railway truck, the combination of a frame; a weight-carrying bolster adapted 65 to traverse laterally relative thereto; pivotal bearing means for the weight on the bolster;

and swing hanger links supporting said bolster, and provided with two upper and two lower bearings, the upper bearings being disposed on opposite sides of a vertical through the outermost of the lower bearings, when the bolster is in normal central relation to the truck.

5. In a railway vehicle, a bolster adapted 70 for lateral movement relative to the vehicle frame structure; linkage means for supporting the bolster from the vehicle frame structure at each side of the vertical center of the bolster; and a pair of bearings for each of the linkage means acting simultaneously when relative movement of the bolster and frame structure takes place, each of said pairs 75 having an upper and a lower bearing, thereby constituting upper and lower pairs, the bearings of one of said last mentioned pairs being disposed normally at unequal distances 80 from the said vertical center.

6. In a railway vehicle, a bolster adapted 85 for lateral movement relative to the vehicle frame structure; linkage means for supporting the bolster from the vehicle frame structure at each side of the vertical center of the bolster; and a pair of bearings for each of the linkage means acting simultaneously 90 when relative movement of the bolster and frame structure takes place whereby the bolster moves away from one pair and toward the other pair of bearings, each of said pairs having an upper and a lower bearing, the bearings of the pair toward which the bolster moves being spaced at a less distance 95 from each other than the bearings of the other pair are spaced from each other, the upper and lower bearings of said pairs constituting upper and lower pairs of bearings, the bearings of one of said last mentioned 100 pairs being disposed normally at unequal distances from the said vertical center.

7. In a railway vehicle, a bolster adapted 105 for lateral movement relative to the vehicle frame structure; linkage means for supporting the bolster from the structure at each side of the vertical center of the bolster; and a plurality of bearings for the linkage means at both top and bottom thereof, arranged for selective grouping for simultaneous acting 110 of the bearings of a group when said relative movement takes place, an upper and a lower bearing on one linkage means, and an upper and a lower bearing on the other linkage means forming a group, the bearings of the group forming upper and lower pairs, the bearings of one of said pairs being normally 115 unequally spaced from said vertical center.

8. In a railway vehicle, a bolster adapted 120 for lateral movement relative to the vehicle frame structure; linkage means for supporting the bolster from the structure at each side of the vertical center of the bolster, the bolster during said lateral movement moving 125 toward one of the linkage means and 130

away from the other of the linkage means; and a plurality of bearings for the linkage means at both top and bottom thereof, arranged for selective grouping for simultaneous acting of the bearings of a group when said relative movement takes place, an upper and a lower bearing on one linkage means, and an upper and a lower bearing on the other linkage means of the group forming pairs, the bearings of the pair on the linkage means toward which the bolster moves being spaced at a lesser distance from each other than the bearings of the other pair are spaced from each other.
